[57] CLAIM

The ornamental design for reversible holder for plant pots, vases or the like, substantially as shown and described.

DESCRIPTION

FIG. 1 is a front elevational view of a reversible holder for plant pots, vases or the like showing my new design; FIG. 2 is a top plan view of FIG. 1;

FIG. 3 is a front elevational view of FIG. 1 in the reversed position;

FIG. 4 is a top plan view of FIG. 3;

FIG. 5 is an enlarged sectional view taken on line 5—5 of FIG. 1;

FIG. 6 is a perspective view of a second embodiment of the design of FIG. 1, the only difference being the omission of the upper and lower rings;

FIG. 7 is a front elevational view of a third embodiment of the design of FIG. 1, the only difference being the substitution of a flat stock for the round wire;

FIG. 8 is a top plan view of FIG. 7;

FIG. 9 is a bottom plan view of FIG. 7; and

FIG. 10 is an enlarged sectional view taken on line 10—10 of FIG. 7.
